HARNESS FRAME CONNECTOR
Henry D. Sweat, 809 Sessions St.,
Soperton, Ga. 30457
Filed July 21, 1966, Ser. No. 566,822
8 Claims. (Cl. 139—88)

This invention relates to new and useful improvements in harness frame connectors for weaving looms.

In accordance with conventional practice, a harness frame has wooden upper and lower rails or sticks, into which are screw-threaded simple hooks for connecting upper and lower harness straps thereto. Under operational strain, the hooks frequently become pulled out and separated from the wooden rails, and valuable time is lost while the loom is stopped and the hooks are re-installed at another point on the rails. Also, when this happens repeatedly, the rails themselves become so damaged that they are no longer capable of properly holding the hooks and must therefore be discarded.

In addition, since the upper harness straps extend vertically downwardly toward the upper rail and the lower straps extend obliquely upwardly toward the lower rail, the hooks on the upper rail are installed perpendicularly while those on the lower rail are oblique, so that the upper and lower hooks are aligned with the directions of pull of the respective straps. This, however, makes the upper and lower rails different from each other, and both types of rails must be carried in stock for replacement parts.

It is, therefore, the principal object of this invention to eliminate the disadvantages above outlined, this object being attained by the provision of an improved connector which may be used selectively and interchangeably on both the upper and lower rails of the harness frame, so that carrying of two different types of rails in stock is unnecessary.

As such, the connector of the invention comprises a block-shaped body which is adapted to be quickly and easily secured to a frame rail by a pair of woodscrews. The body is formed with two screw-threaded bores, one of which is perpendicular while the other is oblique, these bores being adapted to selectively receive a screw-threaded shank of a harness strap attaching hook. Thus, when the connector is used on the upper frame rail, the connector hook is mounted in the perpendicular bore for proper alignment with and connection to the perpendicular upper harness strap. On the other hand, when the connector is used on the lower frame rail, the hook is mounted in the oblique bore for proper alignment with and connection to the oblique lower harness strap.

In either instance, the hook is firmly held in the connector body rather than in the wooden rail, and since the body is firmly secured to the rail, the heretofore experienced difficulty of the hook being pulled out of place is eliminated. Also, the connector body may be secured even to a rail which has been damaged by previous installations of conventional hooks, so that the damaged rail need not be discarded.

As another important feature, the invention provides means for locking the hook against rotation in the connector body.

The connector of the invention is simple in construction, efficient and dependable in use, may be quickly and easily installed on rails of various harness frames, and lends itself to economical manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

2

FIGURE 1 is an elevational view of a harness frame with connectors of the invention applied thereto;

FIGURE 2 is a fragmentary, enlarged perspective view showing one of the connectors on the upper frame rail;

5 FIGURE 3 is a fragmentary, enlarged vertical sectional view of the connector shown in FIGURE 2;

FIGURE 4 is a fragmentary sectional detail, taken substantially in the plane of the line 2—2 in FIGURE 3; and

10 FIGURE 5 is a view, partly in elevation and partly in vertical section, showing one of the connectors on the lower rail.

Referring now to the accompanying drawings in detail, the general reference numeral 10 designates a conventional loom harness frame, including wooden upper and 15 lower rails 11, 12, respectively, connected together by side struts 13, the struts 13 supporting bars 14 which carry a set of heddles 15, as will be clearly apparent. The frame rails 11, 12 are sometimes referred to as sticks or slats.

A pair of upper harness straps 16 extend perpendicularly 20 downwardly toward the upper rail 11, while a pair of lower straps 17 extend obliquely upwardly toward the lower rail 12, the ends of these straps being provided with eyes 18 for connection to hooks which in accordance with conventional practice are screw-threaded directly into the 25 wooden rails 11, 12. In order that the hooks may be properly aligned with the direction of pull of the straps, the hooks on the upper rail are perpendicular while those on the lower rail are oblique, and it will be understood that under the strain of operation, the hooks when screw-threaded directly into the wooden rails frequently become 30 pulled out and must be reinstalled at some other point on the rails.

The improved connector of the invention is designated generally by the reference numeral 20 and is so arranged 35 that it may be used selectively and interchangeably on either end portion of either the upper rail 11 or the lower rail 12. Since all the connectors are the same, a description of one will suffice for all.

Each of the connectors 20 comprises a block-shaped 40 body formed from metal, hard plastic, or the like, the body having a central body portion 21 formed integrally with a pair of lateral ears or wings 22 which are apertured to receive a pair of wood-screws 23 whereby the connector is firmly secured to the associated rail of the harness 45 frame.

The body 21 is formed with a screw-threaded bore 24 which is perpendicular to the base edge 21a of the body, and a second screw-threaded bore 25 is provided in the body obliquely to the base edge. The bores 24, 25 are 50 adapted to selectively receive a screw-threaded shank 26a of a harness strap attaching hook 26.

When the connector 20 is to be used on the upper rail 11 of the frame, the hook shank 26a is installed in the perpendicular bore 24 of the body 21, so that the hook 55 is properly aligned with the direction of pull of the perpendicular upper strap 16. On the other hand, when the connector is used on the lower rail 12, the hook is installed in the oblique bore 25, whereby the hook is obliquely disposed and aligned with the direction of pull of the oblique lower strap 17.

Means are provided for locking the hook against rotation in the connector body, such means involving the provision of additional screw-threaded bores 27, 28 in the body 21, the bore 27 merging into one end portion of the bore 24 and the bore 28 merging into one end portion of the bore 25. The bores 27, 28 accommodate a pair of set screws 29, 30 respectively, for locking engagement with the shank 26a of the hook 26 when the hook shank is installed in either of the bores 24, 25. To attain such locking engagement positively, the set screws 29, 30 preferably have pointed ends as indicated at 31, receivable in a lon-

gitudinal groove 32 formed in the shank 26a of the hook 26, as will be apparent from FIGURES 3-5.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. The combination of a loom harness frame including upper and lower rails, an upper harness strap extending vertically downwardly toward the upper rail, a lower harness strap extending obliquely upwardly toward the lower rail, and upper and lower connectors attaching the respective straps to the respective rails, said upper and lower connectors being identical in construction and therefore usable selectively on the upper and lower rails, each of said connectors comprising a block including a central body and a pair of lateral wings provided with apertures, a pair of mounting screws extending through said wing apertures into the associated rail, said central body being provided with a vertical screw-threaded bore and with an oblique screw-threaded bore, and a harness strap attaching hook having a screw-threaded shank receivable selectively in said vertical and said oblique bores, the hook shank of the upper connector being positioned in the vertical bore for alignment of the hook with the vertical upper harness strap and the hook shank of the lower connector being positioned in the oblique bore for alignment of the hook with the oblique lower strap, said harness straps engaging the hooks of the respective connectors.

2. The combination as defined in claim 1 together with a setscrew provided in the body of each connector for locking a hook shank in the vertical bore.

3. The combination as defined in claim 1 together with a setscrew provided in the body of each connector for locking a hook shank in the oblique bore.

4. The combination as defined in claim 1 wherein the

screw-threaded shank of said hook is provided with a longitudinal groove, and a setscrew provided in the body of each connector, said setscrew entering said groove in the hook shank whereby to lock the hook against rotation.

5. A harness strap connector usable selectively on upper and lower rails of a loom harness frame, said connector comprising a block including a central body and means for mounting said block on a frame rail, said central body being provided with a perpendicular screw-threaded bore and with an oblique screw-threaded bore, and a harness strap attaching hook having a screw-threaded shank receivable selectively in said perpendicular and said oblique bores.

6. The connector as defined in claim 5 together with means for locking said hook shank against rotation in said body.

7. The connector as defined in claim 6 wherein said locking means comprise a setscrew provided in said body and engaging said hook shank.

8. The connector as defined in claim 7 wherein said hook shank is provided with a longitudinal groove, said setscrew entering said groove.
